RHEOSTAT VOLTAGE COMPENSATOR FOR
IGNITION SYSTEMSGeorge E. Michaud, 36 Buchanan Road, Salem, Mass.
Filed Jan. 13, 1961, Ser. No. 82,479
9 Claims. (Cl. 123—143)

This invention relates to ignition systems, and more particularly to ignition systems of the battery-energized type for internal combustion engines.

In a conventional automobile ignition system, the voltage available at the spark plugs decreases with increasing engine speed, because the decreasing interval of contact of the interrupter contacts of the distributor does not permit maximum voltage to be built up in the spark coil. However, the voltage required for proper ignition does not decrease appreciably with increasing speed; and acceleration requires a sharp rise in ignition voltage, because of the accompanying increase in pressure in the compression chamber. Misfiring occurs when the voltage requirement is in excess of that available, and may occur even with new spark plugs in an automobile driven at high speeds or with rapid acceleration. As the spark plug electrodes become worn or the insulators coated with deposits, however, their voltage requirement increases sharply, and misfiring occurs even under moderate speeds and accelerations. While this misfiring may not be noticeable to the operator, it results in a decline in power and efficiency which makes frequent replacement of the spark plugs desirable, although expensive.

This problem cannot be satisfactorily resolved merely by increasing the voltage supplied to the spark plugs by the coil. The high voltage applied to the tungsten interrupter contacts of the distributor causes arcing as they break, and the resulting high temperature in the arc, which may reach 9,000° F. in practice, eventually causes the contacts to become eroded. The rate of erosion depends upon the applied voltage. Similarly, erosion of the spark plug electrodes occurs more rapidly as the applied voltage is increased. The temperature at the gap of the electrodes may momentarily reach 27,000° F. when they are subjected to the maximum voltage available in actual practice. Any increase in voltage above that required for efficient ignition consequently results only in more rapid wear of the interrupter contacts and spark plug electrodes. In order to reduce wear of the contacts and spark plugs, it is a conventional practice to provide 12 volt ignition systems with a fixed resistor to limit the primary ignition voltage to 9 volts. However, this limitation of voltage results in misfiring at an early stage of wear of the spark plugs, under accelerating or high speed conditions, and requires their frequent replacement.

It is the primary object of my invention to provide an improved ignition system having means for increasing the useful life of spark plugs.

It is another object of my invention to provide an improved ignition system having means for preventing misfiring without increasing the rate of wear of spark plug electrodes and interrupter contacts.

It is still another object of my invention to control the voltage supplied to the spark plugs of an ignition system in accordance with the voltage demanded for efficient ignition under various operating conditions.

Further objects and advantages of the invention will become apparent as the following description proceeds.

Briefly stated, I may carry out my invention by inserting a variable resistance element, or rheostat, in series relation in a conventional ignition circuit, and by providing means for controlling the resistance of the rheostat in accordance with the ignition voltage requirement of the engine. These means are arranged to vary the resist-

2

ance as an inverse function of the throttle valve opening, which I have found to be a practical measure of the voltage requirement. Either the throttle position or the manifold pressure may be employed for this purpose.

5 By these means, the voltage applied to the spark plugs is controlled to maintain values which are sufficient to afford efficient ignition under all operating conditions, but which are not so much in excess of ignition requirements as to cause unnecessarily rapid wear of the interrupter points and spark plug electrodes.

10 I further provide means for adjusting the rheostat to obtain a variation in the relationship between the resistance and the control function. By these means, the rheostat may be adjusted to decrease the level of resistance with respect to the control function as the spark plugs become worn, thus increasing the level of the ignition voltage to maintain efficient ignition and provide an extended useful spark plug life. When new plugs are installed, the rheostat is adjusted to increase the level of resistance to 15 values such that while efficient ignition is continued, the secondary voltage is not so much in excess of the required ignition voltage as to cause erosion of the interrupter contacts and the spark plug electrodes at an unnecessarily rapid rate.

20 According to a preferred embodiment of the invention, I provide a rheostat having a rotatable control arm, and drivingly connect the arm with a conventional throttle linkage so that the resistance placed in the circuit of the primary coil is decreased as the throttle is opened by the 25 foot of an operator depressing the accelerator pedal. In this manner, the resistance is controlled in inverse relation to the throttle opening, and is decreased during acceleration of the automobile, as well as during high speed operation. The resistance value of the rheostat is selected 30 to maintain a secondary voltage somewhat in excess of that required throughout the entire speed range of the engine. I also provide an adjustable driving connection between the control arm of the rheostat and the throttle linkage, so that the rate of movement of the arm relative 35 to the throttle lever may be adjusted to conform closely to the voltage requirement.

40 In another embodiment of the invention, the rheostat arm is drivingly connected to a spring-loaded diaphragm which is arranged to be actuated by the pressure obtaining 45 in the engine manifold. This pressure is less than atmospheric pressure, and is therefore conventionally referred to as "vacuum." The pressure increases sharply "low vacuum" during acceleration or at high speed and decreases "high vacuum" at low speeds and during deceleration. The diaphragm is arranged to rotate the arm in a direction to decrease the resistance of the circuit when the engine is accelerated or operated at high speed, thus 50 obtaining a similar result to that achieved by the first embodiment.

55 While the specification concludes with claims particularly pointing out and distinctly claiming the subject matter which I regard as my invention, it is believed that the invention will be more clearly understood from the following detailed description of a preferred embodiment 60 thereof, referring to the accompanying drawing, in which:

FIG. 1 is a schematic representation of an ignition system according to a preferred embodiment of the invention;

FIG. 2 is a diagram comparing the secondary voltage 65 made available to spark plugs by a conventional ignition system with that afforded by the improved system; and

FIG. 3 is a schematic representation of another embodiment of the invention.

Referring to FIG. 1, a preferred embodiment of the 70 invention is shown in combination with the elements of a conventional ignition system. The system includes a battery 1, an ignition switch 2, spark coil 3, a distributor

4, and a plurality of spark plugs, one of which is shown at 5. The ignition switch includes conventional starting and ignition terminals, as designated in the drawing, for energizing a conventional starting motor (not shown) in the starting position, and for de-energizing the starting motor when an associated engine (not shown) is in self-sustaining operation.

The negative terminal of the battery is grounded, while in the starting position of the ignition switch, the positive terminal is connected in series relation with a primary coil of the spark coil 3 through a conductor 6 and a terminal 7. The primary and secondary coils are connected intermittently to a common ground by means of a terminal 8, a conductor 9, a terminal 10, and by an interrupter (not shown) of the distributor 4, which is connected in parallel with a condenser 11. The secondary coil is connected with a distributor arm (not shown) through a conductor 12. The spark plugs receive ignition voltage from the distributor through a plurality of conductors, one of which is shown at 13 connected to the spark plug 5. The ignition system thus far described is well-known in the art, and no further detailed description is believed necessary. I prefer to connect the battery directly to the primary terminal 7 without intervening resistance during starting, in order to provide a maximum starting voltage.

According to customary practice, a fixed resistor would be inserted in series between the battery and the primary coil in the ignition position of the switch, so as to limit the secondary voltage to values just sufficient to fire relatively new spark plugs under high speeds and accelerations, and thus somewhat reduce the rate of wear of the spark plug electrodes and interrupter contacts. However, the use of a fixed resistance also results in misfiring of the spark plugs after a relatively brief period of use, as their voltage requirement rises. In FIG. 2, the relationship between automobile speed and available secondary voltage is graphically depicted. The ignition voltage available in a conventional system, shown in curve A, decreases uniformly with increasing speed, because of the reduction in the interval of engagement of the interrupter contacts. The voltage available is greatly in excess of that required to fire the plugs under the high cylinder pressures associated with low speeds, but is barely sufficient for acceleration and for high-speed operation. The fixed resistance of the system requires that an excessive voltage be supplied at low speeds, thus causing unnecessarily rapid wear of the spark plugs. Furthermore, the voltage requirement rises as the plug electrodes become eroded with wear, and the system may not be capable of satisfying this requirement under conditions of acceleration or at high speed, when cylinder pressure is high, so that misfiring results.

According to the invention, I provide means for controlling the ignition voltage in accordance with engine requirements. Referring again to FIG. 1, these means include a rheostat 14 having a resistance wire 15 helically wound upon an arcuate insulator core 15a. The rheostat is provided with mounting tabs 14a, having elongated fastener-receiving slots 14b for convenient adjustment of the range of resistance afforded by the rheostat, according to the state of wear of the spark plugs. One end of the resistance wire 15 is connected to the conductor 6 by means of an extended terminal 16 and a conductor 17. A control arm or element 18 is rotatably mounted upon the rheostat by means of a clevis pin 19 and a cotter pin 20. An alternative opening 21 for the clevis pin permits the radius of the arm 18, and thus its arcuate range of movement, to be adjusted. The arm carries a contact 22 which is suitably insulated therefrom and connected to the ignition terminal of the switch 2 by means of a conductor 23. The contact is movable along the resistance wire 15 by rotation of the control arm to insert a variable resistance in series relation between the battery and the primary coil when the switch is in the ignition posi-

tion. The extended terminal 16 permits extended clockwise movement of the control arm without further variation in resistance.

The control arm 18 is drivingly connected at its lower end with a throttle linkage including pivotally connected levers 24 and 25, by means of a clevis pin 26 and a cotter pin 27. An alternate opening 28 is formed in the arm to receive the clevis pin, for adjustment of the rate of movement of the arm with respect to the throttle linkage.

10 In a conventional manner, one end of the throttle lever 24 is secured to a foot-operated accelerator pedal 29, which is mounted in an interior surface 29a of the automobile. At its opposite end, the throttle linkage is connected by means of a bell crank 30 and levers 31 and 32 to the throttle valve 33 of a carburetor 34. Depression of the pedal 29 to accelerate the engine or to maintain a relatively high speed causes the arm 18 to rotate in a clockwise direction, decreasing the resistance of the circuit in inverse relation to the throttle valve opening.

15 A diagram of the available voltages in the improved system of FIG. 1 is shown in curve B in FIG. 2. The voltage available remains in excess of that actually required for ignition at all constant speeds, but is limited to values which are not so large as to cause erosion of the electrodes and interrupter points at an unnecessarily rapid rate. It should be noted that the voltage required at constant speeds may be quite low; for example, only 5000 volts may be required at a steady speed of 30 m.p.h. on a level road. Acceleration initially increases cylinder

20 pressure, however, and sharply increases the voltage requirement. In my improved system, opening of the throttle quickly reduces the resistance of the circuit to increase the available voltage. This action is illustrated by curves C and D, showing the voltage made available

25 by the system upon typical accelerations from 30 and 60 m.p.h., respectively. In this manner, the throttle opening serves as an efficient function for controlling the ignition circuit resistance in accordance with ignition voltage requirements.

20 An alternative embodiment of the invention is shown in FIG. 3. In this modification, a variable resistor or rheostat 40 is arranged to be controlled by the pressure obtaining in an intake manifold 41 of an associated internal combustion engine. The rheostat includes a resistance wire 43 wound helically about an arcuate insulator 42 and connected to an extended conducting terminal 44, which serves to permit extended travel of a control arm or element 45 without further variation of resistance.

30 A terminal screw 46 secures a conductor 47 in conductive relation to the terminal. A conductor 48 is connected to a contact 49, which is mounted upon the arm 45 and suitably insulated therefrom, for slidably

35 engaging the resistance wire 43. The conductors 47 and 48 connect the resistance wire in series between a spark coil and a battery or other voltage source (not shown), as in the embodiment of FIG. 1. The arm 45 is pivotally mounted on the rheostat 40 by means of a clevis pin 50

40 and a cotter pin 51. The rheostat is provided with mounting tabs 54 and 55, which are formed with elongated mounting slots 56 and 57, respectively, to permit manual

45 adjustment of the relative position of the resistance element 43 with respect to the arm 45. The level of resistance corresponding to various levels of manifold pressure may thus be adjusted to accommodate both old and new spark plugs, in a manner similar to that previously

50 described in the embodiment of FIG. 1.

55 A throttle lever 59 is secured by means of a clevis pin 60 and a link 61 to the throttle valve 63 of a carburetor 64, and the carburetor is mounted upon the intake manifold 41 in a conventional manner. The degree of "vacuum" obtaining in the intake manifold varies in inverse

60 response to the acceleration and speed of the engine, and to the throttle opening. I utilize the vacuum as a control function to modulate the resistance of the ignition

65 circuit by providing a diaphragm 70 drivingly connected

70 to the control arm 45. The diaphragm 70 is connected to the intake manifold 41 by a tube 71, and is biased

75 to a position in which the diaphragm 70 is in contact with the intake manifold 41.

80 The diaphragm 70 is provided with a central opening 72, and the tube 71 is connected to the central opening 72 of the diaphragm 70. The tube 71 is connected to the intake manifold 41 by a tube 73.

85 The tube 73 is connected to the intake manifold 41 by a tube 74.

90 The tube 74 is connected to the intake manifold 41 by a tube 75.

95 The tube 75 is connected to the intake manifold 41 by a tube 76.

100 The tube 76 is connected to the intake manifold 41 by a tube 77.

105 The tube 77 is connected to the intake manifold 41 by a tube 78.

110 The tube 78 is connected to the intake manifold 41 by a tube 79.

115 The tube 79 is connected to the intake manifold 41 by a tube 80.

120 The tube 80 is connected to the intake manifold 41 by a tube 81.

125 The tube 81 is connected to the intake manifold 41 by a tube 82.

130 The tube 82 is connected to the intake manifold 41 by a tube 83.

135 The tube 83 is connected to the intake manifold 41 by a tube 84.

140 The tube 84 is connected to the intake manifold 41 by a tube 85.

145 The tube 85 is connected to the intake manifold 41 by a tube 86.

150 The tube 86 is connected to the intake manifold 41 by a tube 87.

155 The tube 87 is connected to the intake manifold 41 by a tube 88.

160 The tube 88 is connected to the intake manifold 41 by a tube 89.

165 The tube 89 is connected to the intake manifold 41 by a tube 90.

170 The tube 90 is connected to the intake manifold 41 by a tube 91.

175 The tube 91 is connected to the intake manifold 41 by a tube 92.

180 The tube 92 is connected to the intake manifold 41 by a tube 93.

185 The tube 93 is connected to the intake manifold 41 by a tube 94.

190 The tube 94 is connected to the intake manifold 41 by a tube 95.

195 The tube 95 is connected to the intake manifold 41 by a tube 96.

200 The tube 96 is connected to the intake manifold 41 by a tube 97.

205 The tube 97 is connected to the intake manifold 41 by a tube 98.

210 The tube 98 is connected to the intake manifold 41 by a tube 99.

215 The tube 99 is connected to the intake manifold 41 by a tube 100.

220 The tube 100 is connected to the intake manifold 41 by a tube 101.

225 The tube 101 is connected to the intake manifold 41 by a tube 102.

230 The tube 102 is connected to the intake manifold 41 by a tube 103.

235 The tube 103 is connected to the intake manifold 41 by a tube 104.

240 The tube 104 is connected to the intake manifold 41 by a tube 105.

245 The tube 105 is connected to the intake manifold 41 by a tube 106.

250 The tube 106 is connected to the intake manifold 41 by a tube 107.

255 The tube 107 is connected to the intake manifold 41 by a tube 108.

260 The tube 108 is connected to the intake manifold 41 by a tube 109.

265 The tube 109 is connected to the intake manifold 41 by a tube 110.

270 The tube 110 is connected to the intake manifold 41 by a tube 111.

275 The tube 111 is connected to the intake manifold 41 by a tube 112.

280 The tube 112 is connected to the intake manifold 41 by a tube 113.

285 The tube 113 is connected to the intake manifold 41 by a tube 114.

290 The tube 114 is connected to the intake manifold 41 by a tube 115.

295 The tube 115 is connected to the intake manifold 41 by a tube 116.

300 The tube 116 is connected to the intake manifold 41 by a tube 117.

305 The tube 117 is connected to the intake manifold 41 by a tube 118.

310 The tube 118 is connected to the intake manifold 41 by a tube 119.

315 The tube 119 is connected to the intake manifold 41 by a tube 120.

320 The tube 120 is connected to the intake manifold 41 by a tube 121.

325 The tube 121 is connected to the intake manifold 41 by a tube 122.

330 The tube 122 is connected to the intake manifold 41 by a tube 123.

335 The tube 123 is connected to the intake manifold 41 by a tube 124.

340 The tube 124 is connected to the intake manifold 41 by a tube 125.

345 The tube 125 is connected to the intake manifold 41 by a tube 126.

350 The tube 126 is connected to the intake manifold 41 by a tube 127.

355 The tube 127 is connected to the intake manifold 41 by a tube 128.

360 The tube 128 is connected to the intake manifold 41 by a tube 129.

365 The tube 129 is connected to the intake manifold 41 by a tube 130.

370 The tube 130 is connected to the intake manifold 41 by a tube 131.

375 The tube 131 is connected to the intake manifold 41 by a tube 132.

380 The tube 132 is connected to the intake manifold 41 by a tube 133.

385 The tube 133 is connected to the intake manifold 41 by a tube 134.

390 The tube 134 is connected to the intake manifold 41 by a tube 135.

395 The tube 135 is connected to the intake manifold 41 by a tube 136.

400 The tube 136 is connected to the intake manifold 41 by a tube 137.

405 The tube 137 is connected to the intake manifold 41 by a tube 138.

410 The tube 138 is connected to the intake manifold 41 by a tube 139.

415 The tube 139 is connected to the intake manifold 41 by a tube 140.

420 The tube 140 is connected to the intake manifold 41 by a tube 141.

425 The tube 141 is connected to the intake manifold 41 by a tube 142.

430 The tube 142 is connected to the intake manifold 41 by a tube 143.

435 The tube 143 is connected to the intake manifold 41 by a tube 144.

440 The tube 144 is connected to the intake manifold 41 by a tube 145.

445 The tube 145 is connected to the intake manifold 41 by a tube 146.

450 The tube 146 is connected to the intake manifold 41 by a tube 147.

455 The tube 147 is connected to the intake manifold 41 by a tube 148.

460 The tube 148 is connected to the intake manifold 41 by a tube 149.

465 The tube 149 is connected to the intake manifold 41 by a tube 150.

470 The tube 150 is connected to the intake manifold 41 by a tube 151.

475 The tube 151 is connected to the intake manifold 41 by a tube 152.

480 The tube 152 is connected to the intake manifold 41 by a tube 153.

485 The tube 153 is connected to the intake manifold 41 by a tube 154.

490 The tube 154 is connected to the intake manifold 41 by a tube 155.

495 The tube 155 is connected to the intake manifold 41 by a tube 156.

500 The tube 156 is connected to the intake manifold 41 by a tube 157.

505 The tube 157 is connected to the intake manifold 41 by a tube 158.

510 The tube 158 is connected to the intake manifold 41 by a tube 159.

515 The tube 159 is connected to the intake manifold 41 by a tube 160.

520 The tube 160 is connected to the intake manifold 41 by a tube 161.

525 The tube 161 is connected to the intake manifold 41 by a tube 162.

530 The tube 162 is connected to the intake manifold 41 by a tube 163.

535 The tube 163 is connected to the intake manifold 41 by a tube 164.

540 The tube 164 is connected to the intake manifold 41 by a tube 165.

545 The tube 166 is connected to the intake manifold 41 by a tube 167.

550 The tube 168 is connected to the intake manifold 41 by a tube 169.

555 The tube 170 is connected to the intake manifold 41 by a tube 171.

560 The tube 172 is connected to the intake manifold 41 by a tube 173.

565 The tube 174 is connected to the intake manifold 41 by a tube 175.

570 The tube 176 is connected to the intake manifold 41 by a tube 177.

575 The tube 178 is connected to the intake manifold 41 by a tube 179.

580 The tube 180 is connected to the intake manifold 41 by a tube 181.

585 The tube 182 is connected to the intake manifold 41 by a tube 183.

590 The tube 184 is connected to the intake manifold 41 by a tube 185.

595 The tube 186 is connected to the intake manifold 41 by a tube 187.

600 The tube 188 is connected to the intake manifold 41 by a tube 189.

605 The tube 190 is connected to the intake manifold 41 by a tube 191.

610 The tube 192 is connected to the intake manifold 41 by a tube 193.

615 The tube 194 is connected to the intake manifold 41 by a tube 195.

620 The tube 196 is connected to the intake manifold 41 by a tube 197.

625 The tube 198 is connected to the intake manifold 41 by a tube 199.

630 The tube 200 is connected to the intake manifold 41 by a tube 201.

635 The tube 202 is connected to the intake manifold 41 by a tube 203.

640 The tube 204 is connected to the intake manifold 41 by a tube 205.

645 The tube 206 is connected to the intake manifold 41 by a tube 207.

650 The tube 208 is connected to the intake manifold 41 by a tube 209.

655 The tube 210 is connected to the intake manifold 41 by a tube 211.

660 The tube 212 is connected to the intake manifold 41 by a tube 213.

665 The tube 214 is connected to the intake manifold 41 by a tube 215.

670 The tube 216 is connected to the intake manifold 41 by a tube 217.

675 The tube 218 is connected to the intake manifold 41 by a tube 219.

680 The tube 220 is connected to the intake manifold 41 by a tube 221.

685 The tube 222 is connected to the intake manifold 41 by a tube 223.

690 The tube 224 is connected to the intake manifold 41 by a tube 225.

695 The tube 226 is connected to the intake manifold 41 by a tube 227.

700 The tube 228 is connected to the intake manifold 41 by a tube 229.

705 The tube 230 is connected to the intake manifold 41 by a tube 231.

710 The tube 232 is connected to the intake manifold 41 by a tube 233.

715 The tube 234 is connected to the intake manifold 41 by a tube 235.

720 The tube 236 is connected to the intake manifold 41 by a tube 237.

725 The tube 238 is connected to the intake manifold 41 by a tube 239.

730 The tube 240 is connected to the intake manifold 41 by a tube 241.

735 The tube 242 is connected to the intake manifold 41 by a tube 243.

740 The tube 244 is connected to the intake manifold 41 by a tube 245.

745 The tube 246 is connected to the intake manifold 41 by a tube 247.

750 The tube 248 is connected to the intake manifold 41 by a tube 249.

755 The tube 250 is connected to the intake manifold 41 by a tube 251.

760 The tube 252 is connected to the intake manifold 41 by a tube 253.

765 The tube 254 is connected to the intake manifold 41 by a tube 255.

770 The tube 256 is connected to the intake manifold 41 by a tube 257.

775 The tube 258 is connected to the intake manifold 41 by a tube 259.

780 The tube 260 is connected to the intake manifold 41 by a tube 261.

785 The tube 262 is connected to the intake manifold 41 by a tube 263.

790 The tube 264 is connected to the intake manifold 41 by a tube 265.

795 The tube 266 is connected to the intake manifold 41 by a tube 267.

with the control arm 45 by means of a link 71. The link is secured to the control arm by means of a clevis pin 72 and a cotter pin 73, and is cemented to the diaphragm or secured thereto in any other suitable manner. The diaphragm is peripherally sealed within a casing 74 to form an air-tight chamber 75 and a chamber 76 which is open to the atmosphere through an opening 77 formed in the casing. A compression spring 78 is disposed in a cylindrical portion 79 of the casing to urge the diaphragm and the link toward the right as viewed in FIG. 3. A conduit 80 communicates with the manifold 41 and with the chamber 75 through conventional air-tight fittings 81 and 82, respectively. The manifold pressure is thus applied to the diaphragm 70, in opposition to the atmospheric pressure in the chamber 76. The manifold pressure, which is normally less than atmospheric, permits the atmospheric pressure to urge the lever 71 and the arm 45 toward the left as viewed in FIG. 3, against the bias of the spring 78.

By these means, the position of the control arm 45 and the ignition circuit resistance are regulated in direct response to the degree of manifold vacuum, which is an inverse function of the speed and acceleration of the engine, and of the throttle opening. I have found that the manifold vacuum is an adequate control function; however, I prefer to utilize throttle opening directly as the control function, as in the embodiment of FIG. 1, because of the greater sensitivity of the latter with respect to ignition voltage requirements.

While I have shown and described preferred embodiments of my invention for purposes of illustration, it will be apparent to those skilled in the art that various changes and modifications may be made without departing from the spirit and scope of the invention. I therefore intend to cover all such changes and modifications in the appended claims.

What I claim and desire to secure by Letters Patent of the United States is:

1. Apparatus adapted for controlling the ignition voltage supplied by means of an ignition circuit to a spark plug of an internal combustion engine having a throttle valve, said apparatus comprising, in combination: a rheostat in electrical series relation in said ignition circuit, said rheostat having a movable control element for varying the resistance thereof, and means drivingly connected with said control element for controlling the resistance of said rheostat as a continuous inverse function of the opening of the throttle valve of the engine independently of the engine speed.

2. For use in an internal combustion engine having a throttle valve, an ignition circuit and a spark plug for the ignition of fuel; the combination with said ignition circuit of a rheostat interposed in electrical series relation therein, a movable control element for varying the resistance of said rheostat, and means responsive to the opening of the throttle valve, said means drivingly connected with said control element to vary the resistance of said ignition circuit in inverse relation to the opening of the throttle valve, independently of the engine speed.

3. The combination recited in claim 2, in which the driving connection between said control element and said means is adjustable to provide an adjustable relationship between the resistance of said ignition circuit and the opening of the throttle valve.

4. In an internal combustion engine having a throttle valve movable between open and closed positions for controlling the speed and acceleration of the engine, a throttle lever manually movable to control the opening of said throttle valve, and an ignition circuit including a spark plug for ignition of fuel, the combination therewith of a rheostat interposed in electrical series relation in said ignition circuit, and a movable control element for varying the resistance of said rheostat, said throttle lever be-

ing drivingly connected with said control element to vary the resistance of said ignition circuit in inverse relation to the opening of said throttle valve, independently of the engine speed.

5. The combination recited in claim 4, in which said throttle lever is adjustably connected with said control element for adjustment of the relationship between the resistance of said ignition circuit and the opening of said throttle valve.

6. In an internal combustion engine having a throttle valve movable between open and closed positions for controlling the speed and acceleration of the engine, a throttle lever manually movable to control the opening of said throttle valve, and an ignition circuit including a source of voltage, a spark coil, and a spark plug arranged in series relation for ignition of fuel; the combination therewith of an elongated resistance element, a control element, and a contact carried by said control element in slidably engagement with said resistance element, said contact and said resistance element being interposed in electrical series relation between said source of voltage and said coil, said control element being rotatably supported for varying the resistance of said ignition circuit, said throttle lever being drivingly connected with said control element to vary the resistance of said ignition circuit in inverse relation to the opening of said throttle valve, independently of the engine speed.

7. In an internal combustion engine having a fuel mixture intake manifold in which the pressure varies in relation to the speed and acceleration of the engine, and an ignition circuit including a spark plug for ignition of the fuel mixture; the combination therewith of a rheostat interposed in electrical series relation in said ignition circuit, a movable control element for varying the resistance of said rheostat, and pressure-responsive means in communication with said manifold and drivingly connected with said control element to vary the resistance of said circuit in inverse relation to the pressure in said intake manifold, independently of the engine speed.

8. The combination recited in claim 7, in which said pressure-responsive means is adjustably connected with said control element for adjustment of the relationship between the resistance of said ignition circuit and the pressure in said intake manifold.

9. In an internal combustion engine having a throttle valve movable between open and closed positions for controlling the speed and acceleration of the engine, a fuel mixture intake manifold in which the pressure varies in relation to the opening of the throttle valve, and an ignition circuit including a source of voltage, a spark coil, and a spark plug arranged in series relation for ignition of fuel; the combination therewith of an elongated resistance element, a control element, a contact carried by said control element in slidably engagement with said resistance element, said contact and said resistance element being interposed in electrical series relation between said source of voltage and said coil, said control element being rotatably supported for varying the resistance of said ignition circuit, and pressure-responsive means in communication with said manifold and drivingly connected with said control element to vary the resistance of said ignition circuit in inverse relation to the pressure in said intake manifold, independently of the engine speed.
